ASH TRAY

Simon Pollak, New York, N. Y.

Application October 9, 1947, Serial No. 141,813

Term of patent 14 years

(Cl. D85—2)

To all whom it may concern:

Be it known that I, Simon Pollak, a citizen of the United States, residing at New York in the county of New York and State of New York, have invented a new, original, and ornamental Design for an Ash Tray, of which the following is a specification, reference being had to the accompanying drawing, forming a part thereof.

In the drawing:

Fig. 1 is a plan view of an ash tray, showing my new design;

Fig. 2 is a bottom view of the same.

Fig. 3 is a vertical sectional view taken on the line 3—3 of Fig. 1.

I claim:

The ornamental design for an ash tray, as shown.

SIMON POLLAK.
